United States Patent Office

Des. 189,368
Patented Nov. 29, 1960

189,368

ROOM THERMOSTAT OR SIMILAR ARTICLE

Albert E. Baak, 640 Ocampo Drive, Pacific Palisades,
Calif.

Filed June 20, 1960, Ser. No. 61,044

Term of patent 14 years

(Cl. D52—7)

Fig. 1 is a perspective view of a room thermostat, showing my new design;

Fig. 2 is a front elevational view thereof; and

Fig. 3 is a side elevational view thereof.

The essential features of my design reside in the portions shown in solid lines.

I claim:

The ornamental design for a room thermostat or similar article, substantially as shown and described.
